FRED L. CROFT, OF COALINGA, CALIFORNIA.

ENGINE VALVE.

Application filed May 25, 1927. Serial No. 194,217.

The object of this invention is to provide a special form of valve, or valves, for controlling the inlet and exhaust connections of an internal combustion engine.

- 5 A further object is to provide a slide valve for controlling each port, the valve being mounted in the wall of the cylinder, and the valve chamber being directly above the crank case, on each side, and being closed, so that
 10 oil agitated in the crank case will pass into the valve chamber to a sufficient extent to provide lubrication, and the oil, thus employed, or any slight excess, will flow back to the crank casing.
 15 A further object is to provide a slide valve of the special construction disclosed below, this valve being guided in a particular manner, and being operated from a cam shaft within the crank casing, and on each side
 20 thereof.

With the foregoing and other objects in view, the invention consists in the novel construction and arrangement of elements described, illustrated and claimed, it being understood that modifications may be made within the scope of the claim without departing from the spirit of the invention.

In the drawings forming part of this application,

- 30 Figure 1 is a vertical section thru an engine cylinder, and a portion of the crank casing.

- Figure 2 is a horizontal section through the cylinder walls, and above the piston of
 35 Figure 1.

- Figure 3 is a fragmentary view in elevation, showing a portion of a cylinder and a portion of the crank case, the outer wall or cover portions of the valve chamber being broken away, to show the slide valve and the mounting means therefor.

Figure 4 is a perspective view of the valve per se.

- Figure 5 shows another form of mounting, the valve being on the outer curved wall of a cylinder, a portion of which is illustrated.

- The engine cylinder 10 is provided with a lateral extension, as shown in part at 11, and is provided with usual water chambers, the intake port being designated 12, and the exhaust port being shown at 13. A manifold 14 on the intake side serves an obvious purpose and is in communication with port 12 thru one of the slide valves, and the exhaust manifold 15 is in communication with port

13. The piston within the cylinder 10 is designated 17 and is carried by or has connection with rod 18 passing into crank casing 19.

Within the crank casing 19 are shafts 20 carrying cams 21 adapted to operate the elements 22 thru which movement is imparted to valve stems such as 23 within each outer chamber 24.

The valve chamber is closed by cover plates such as 26 and 27, these being independently detachable for reasons clearly apparent to those familiar with this class of apparatus.

The valves 30 are of the form shown in Figure 4 in perspective, and are each provided with a port 31, and with flanges 32 on opposite sides, these flanges being guided within the portions 33 extending from the cylinders, and it will be observed that the main or central portions of the valves are curved in conformity with the curvature of the cylinder walls.

Tappets are shown at 22, and jam nuts are 80 designated 23', and the stems 23 are vertically movable for the purpose of operating the valves, said stems passing thru bushings 36, and the elements 22 passing thru bushings 36'. Each stem carries a collar 38 engaged by spring 39, the latter surrounding the stem 23 and engaging at its upper end the element 36" projecting from the cylinder wall. The valves are operable in contact with compression elements such as those shown at 41. 90

In the form of Figure 5, valve 30' is provided with flanges 32', and the valve is mounted in guides 40 on the outer wall 10' of a cylinder.

The operation of valves of this type is efficient and reliable, and they include mounting means adapted to be lubricated without attention on the part of the operator of the car, dependence being placed in part on the splashing of oil in the crank case, and the passage of a sufficient quantity thereof into the chambers at the sides of the cylinder. Adjustment of the tappet and jam nut on each side provides for the adjustment of the valve. The upper element 27 of the cover is provided with an inwardly extending flange at 27', and this flange, as well as the flat surface of the cover, aids in guiding and retaining the valve 30.

Having described the invention what is claimed is:—

The combination with an engine cylinder

having a port in the wall thereof, of a slide valve controlling the port, said valve including a stem and including edge flanges extending outwardly therefrom, the cylinder wall including means for guiding the edge portions of the valve, a chamber being provided in the wall, detachable means for closing the chamber, projecting between the flanges of

the valve, and aiding in guiding the valve, a cam shaft adapted to be mounted in the crank casing, an element operated by the shaft and cam, and adjustable means carried by the stem and adapted for engagement by the element operated from the cam shaft. ¹⁰

In testimony whereof I affix my signature.

FRED L. CROFT.
